UNITED STATES PATENT OFFICE.

ORVILLE MERTON KILE, OF BALTIMORE, MARYLAND.

CALCULATING DEVICE.

1,304,781.

Specification of Letters Patent. Patented May 27, 1919.

Application filed March 27, 1918. Serial No. 225,005.

To all whom it may concern:

Be it known that I, ORVILLE M. KILE, a citizen of the United States, residing at Baltimore, in the State of Maryland, have invented certain new and useful Improvements in Calculating Devices, of which the following is a specification.

The present invention relates to a method and apparatus for determining proportions of various substances in compounds and mixtures wherein a given ratio will be secured and indicated in reference to two variable properties or characteristics of the ingredients together with the quantities or amounts of the ingredients, while at the same time permitting, at any stage of the operation, substitution of other ingredients and variation of the relative amounts of the individual ingredients of the proposed mixture or compound.

The object of the invention is to provide a simple, practical and efficient calculating device, of strong, durable and comparatively inexpensive construction equipped with ingredient scales and means for indicating the variable properties or characteristics of the ingredients, actuated by mechanism controlled by pointers movable over the ingredient scales for indicating the number and amount of the ingredients and the sum of their variable properties or characteristics, whereby the desired amounts and proportions of the two characteristics or properties and approximately the desired amounts and proportions of the various constituents of the proposed mixture may be obtained.

It is also an object of the invention to provide an adjustable table associated with the indicating devices and adapted to bring into convenient position with relation to exposed portions of the indicating devices any of its items of contents so that the variables may be made to correspond to the workings of the adjustable table to produce a variety of compounds or mixtures for various conditions and purposes with accuracy and ease.

The invention consists generally in reducing the two desired properties or characteristics found in the given or possible constituents to two sets of scales, one set evaluated into spaces according to the relative amounts of one characteristic of the ingredients and the other set of scales evaluated according to the amounts of the other characteristic of the same ingredients, and in also providing separate connected indicating means for reg-

istering the amounts of the two characteristics of the constituents, and associated in such a way as to readily indicate the desired ratio of the same in the proposed mixture. 60

The invention also consists in the novel construction, combination and arrangement of the parts of the calculating device, hereinafter fully described, illustrated in the accompanying drawings and pointed out in the claims hereto appended, it being understood that various changes in the form, proportion and minor details of construction, within the scope of the claims may be resorted to without departing from the spirit 70 or sacrificing any of the advantages of the invention.

In the drawing:

Figure 1 is an elevation of a calculating device constructed in accordance with this 75 invention;

Fig. 2 is a longitudinal sectional view of the same;

Fig. 3 is a transverse sectional view on the line 3—3 of Fig. 2; 80

Fig. 4 is a similar view on the line 4—4 of Fig. 2.

Fig. 5 is a longitudinal sectional view of a portion of the device illustrating another form of operating means. 85

Fig. 6 is a perspective view of the calculating device.

Like numerals of reference designate corresponding parts in the several figures of the drawing. 90

In the accompanying drawing in which is illustrated the preferred form of calculator, 1 designates a cylindrical casing constructed of any suitable material and having end walls 2, supporting a central longitudinal shaft or axle 3 upon which are mounted hollow shafts or sleeves 4 and 5 carrying at their inner ends rotary indicator drums 6 and 7 and having mounted on them at their outer portions toothed wheels 8 and 9. The 95 drums 6 and 7, the wheels 8 and 9 are fixed to the sleeves 4 and 5 but any other suitable means may be employed for transmitting motion from the wheels 8 and 9 to the drums 6 and 7. The drums 6 and 7 are provided with 100 graduated rims 10 and 11, the graduations 12 and 13 being consecutively numbered and a portion of the drums 6 and 7 being exposed at a sight opening 14 in the front of the casing 1. 105

The toothed wheels 8 and 9 which are spaced apart, are actuated by operating le-

vers 15 and 16 fulcrumed intermediate of their ends on the sleeves 4 and 5 and provided with openings 17. The inner ends of the levers are provided with laterally projecting dogs 18 adapted to engage the teeth of the wheels 8 and 9 and normally maintained out of engagement with the same by springs 19 located in the openings 17 and disposed on rods or stems 20 and interposed between shoes 21 of the rods or stems 20 and the inner end walls of the openings 17. The rods or stems 20 are slidably mounted in the levers, which are provided at their outer portions with laterally projecting pointers 22 to coöperate with scales 23 and 24 located adjacent to arcuate slots 25 and 26 formed in the front of the cylindrical casing 1 and through which the operating levers 15 and 16 project. The levers 15 and 16 have projecting heads 25' and the pointers 22 are tapered inwardly at 27 to engage notches 28 located at the sides of the scales 23 and 24 and corresponding to the graduations thereof so that the levers may be accurately positioned along the scales at the end portions of the casing. The springs maintain the levers in engagement with the scale notches and when it is desired to adjust a lever it is drawn outwardly grasping its projecting head and its outward movement disengages its outer portion from the engaged scale notch and carries its lug or tooth 18 into engagement with the coacting toothed wheel and when the lever is oscillated the toothed wheel and the sleeve, upon which it is mounted is partially rotated together with the indicating drum carried by the sleeve to add or subtract according to the direction of movement of the lever. The levers may be independently adjusted and when one of the levers at one end of the casing is adjusted for changing the indication on the drum of the characteristic controlled by it, the corresponding lever at the other end of the casing is adjusted to effect a change in the other characteristic indicated on the other drum to preserve the ratio between the two indicated characteristics.

The drums are spaced apart at the center of the casing, and the shaft 3 which is fixed, has mounted on it washers 29 forming collars and spaced apart to receive a rotary adjustable disk 30 and coiled springs 31 disposed on the shaft 3 and interposed between the washers 29 and the disk 30 to prevent accidental movement of the same and to thereby retain the disk in its adjustment. The disk constitutes the web of a wheel or member having a transparent rim 32, which projects laterally over the periphery of the drums 6 and 7, the disk is of slightly greater diameter than the drums 6 and 7 and the transparent rim 32 is arranged close to the inner face of the casing and is of a width to extend beyond the ends of the opening 14

and it forms a window for the same capable of rotary adjustments to present to view different portions of its surface and table or ratio indications 33 carried by the same so that the indications on the drums may be made to correspond with any set of ratio indications on the rotary table carrying wheel or member. The rotary transparent rim indicates properly balanced rations and is adapted to be rotated to bring such balanced rations into view as a guide to the setting of the indicator drums 6 and 7 in the making up of such a ration from the ingredients on hand.

The rim 32 is provided near one edge with spaced perforations 34 and the casing has a slot 35 at the back to permit a pin or other instrument to be introduced into the casing and engaged with a perforation of the rim for rotating the table-carrying wheel or member to bring any portion of its rim 32 to the opening 14 of the casing to coöperate with the indicating drums, so that the ratio indicated on the drum by the same may be made to correspond with a ratio indication of the rim 32.

The calculator may be employed for obtaining various ratios of ingredients of various compounds or mixtures and when used for calculating a balanced dairy ration the operation would be as follows:—The scales at the end portions of the casing are evaluated for listing the protein and thermal units of various common feed stuffs in pounds or other unit of weight of such materials. The number of the scales may be varied and for convenience they would be arranged for listing roughages and concentrates. In operation, several levers in the protein end of the casing would be moved and set at trial positions on the scales determined by the relative quantities and values of the different possible feeds that are available. The corresponding number of units of protein would be indicated on the indicator drum 7. The levers in the "therms" end would then be set to correspond exactly to the same quantities of exactly the same feeds and the corresponding therms would likewise be indicated by the drum 6. These quantities would then be compared with the predetermined quantities, as printed on the adjustable transparent window directly over the drum scales, and additions and subtractions would then be made by shifting the levers until the indicated units of protein and thermal energy would be identical with the predetermined required amounts. Opportunity is still offered for further substitution to reduce costs and the evaluated scales form an accurate guide for these possible substitutions. Whenever the drums 6 and 7 register the required number of units the various grains or other feed stuff may be mixed in the quantities indicated by the pointers of the various levers or

in multiples thereof and maintains the proportionate characteristics.

The rotary table-carrying wheel or member enables the calculator to be adjusted so as to figure suitable rations or variations to suit any number of conditions, as for instance, large cows and small cows, heavy milkers and light milkers, cows on early spring pasture or on late summer pasture, or even change to rations for horses, sheep or any other kind of animal. Since the variations in each case means that the animal must have a total of a different number of units of protein and thermal units, all that is required is to mark the rotary wheel or member with exactly the amounts of the two units required to meet the various conditions of feeding.

A farmer would have certain feeds on his farm such as corn, oats, clover or alfalfa hay, corn, silage, etc. He would expect to buy certain concentrated feeds like cotton seed meal, brewers' grains or perhaps some commercial preparations. His problem is to use what feeds he has, buy the cheapest feed necessary to balance his ration and then mix the whole so as to have the right proportions of protein and thermal units. Certain general rules will accompany the calculator, as indicated in Fig. 6 of the drawing for instance, when a lever at one end is operated to add one characteristic of an ingredient, a lever at the opposite end of the calculator must be operated to add the other characteristic contained in such ingredient, the total amount of dry material fed to a cow must be not less than thirty-five pounds and not more than forty-five pounds. Also the object would generally be to use as large a proportion of home produced feed as possible and simply balance up with the purchased feed, which is high in protein, the element generally lacking in home grown feeds. Another rule should state that not over six pounds of concentrates should be fed to an animal.

Suppose a farmer has silage to feed, also clover hay. He knows he must get considerable of the bulk from these sources. He would then move down the levers for roughages on the extreme left, one representing hay and the other silage until their combined weights amounted to about thirty pounds using more or less of one or the other according to the supply available. The corresponding two levers on the extreme right would then be moved down to exactly the same positions or until they were opposite exactly the same number of pounds of these two feeds. The movements of these levers would cause movements of the indicator drums at the sight aperture 14 to register the amount of protein and thermal units respectively. The operator could see at a glance that while he had reached high

up toward the limit of total weight, yet the registered ingredients were still quite low. He would therefore put in some concentrate, probably corn and move down two levers, one at each end, indicating the amount of corn. Probably this will show that the registered thermal units have gone away up above the total amount required, while the protein is still too low. The only thing to do is to take out some of the corn, moving the levers back, and put in a concentrate that runs high in protein. This the farmer usually has to buy and so can take his choice using the one that gives him the protein cheapest. Probably after adding enough of this purchased concentrate to bring the protein up to the required total, moving the proper levers, he finds he has too many thermal units or perhaps he has taken more than the allowable six pounds of concentrated feed to get the correct register. This means that more roughages and less grain must be used and so the levers are shifted to make the correction. Here is where the chance for skill and profit comes in. By making certain substitutions, perhaps money and feed can be saved.

When the central indicating drums register the proper marked amounts, the right proportions for the health and highest production of the animal are obtained and the feed can be mixed accordingly. For convenience every ingredient would be multiplied by one hundred, and thus three pounds of corn would become three hundred pounds in the actual mixture. This mixed stock would then be used to feed for weeks at a time and then could be remixed according to same formula until prices changed or new feed had to be substituted.

In Fig. 5 of the drawing is illustrated a simpler form of operating means comprising an operating lever 36 fulcrumed at its inner end 37 on the sleeve 38 adjacent the toothed wheel 39 and constructed of resilient material and normally engaging at its outer portion, notches or serrations 40 formed in one of the side walls of the slot 41. The lever 36 which is equipped at its outer end with a pointer 42 is adapted to be flexed laterally and sprung out of engagement with the serrations or notches and this lateral movement carries a tooth or pin 43 into engagement with the toothed wheel 39. The lever is then adapted to be oscillated to partially rotate the toothed wheel and when the desired amount of movement has been imparted to the operating lever it will automatically spring into engagement with the notched or serrated edge of the slot and simultaneously disengage its pin or tooth 43 from the wheel 39. The operating means illustrated in Fig. 5 may be constructed at a low cost and while two forms of operating means are illustrated in the accompanying

drawing it will be apparent that any equivalent operating means may be used for this purpose.

What I claim is:

- 5 1. The herein described method of determining the relative proportions of various substances to be mixed or compounded to produce a mixture wherein a given ratio will be secured in reference to two variables, 70
10 which consists in arranging indicating means designating the ratio of the variables in the required mixture and in successively adding or subtracting the ratios of the two variables in a plurality of ingredients and 15 varying the ingredients to provide a mixture corresponding with the ratio of the said indicating means.
2. An apparatus of the class described, including means for successively adding the 20 ratios of variables contained in any ingredients of a mixture, to ascertain the ratio of the variables of the mixture, for subtracting the ratios of the variables of ingredients to enable one ingredient to be substituted for another to produce a mixture having a given ratio of the variables and an adjustable indicating means having sets of corresponding ratios of variables and adapted to be arranged to present a set 25 of ratios to form a guide for making the said mixture.
3. In an apparatus for the purpose described, the combination of an outer casing, of substantially cylindrical form bearing 30 near each end, one or more evaluated scales, one for one characteristic on the right hand and another for a second characteristic on the left hand, said casing having slots at the scales, a shaft or axle carried by and extending longitudinally of the cylinder, a plurality of levers pivoted on the shaft or axle and extending through the slots and having pointers movable over the scales, separate indicating means operated by the 35 levers and a rotary device having a plurality of sets of corresponding ratios of variables adapted to be adjusted to present a set of ratios to form a guide.
4. A calculator of the class described including a casing having evaluated scales, separate sets of operating devices having pointers moving over the scales, separate indicating means connected with and actuated by operating devices, and a rotary device having a plurality of sets of corresponding ratios of variables adapted to be adjusted to present a set of ratios to form a guide.
5. A calculator of the class described including a casing having a plurality of scales evaluated with reference to two variable characteristics, separate sets of operating means having pointers movable over the scales, separate indicating means connected with and actuated by the operating means 40 for registering the amounts of the characteristics and a rotary device having a plurality of sets of corresponding ratios of variables adapted to be adjusted to present a set of ratios to form a guide. 75
6. The calculator of the class described, including a casing having a plurality of scales evaluated with reference to two variable characteristics, separate operating members having pointers movable over the scale, 75 separate rotary indicating drums connected with and actuated by the levers for registering separate amounts of characteristics for indicating the ratios thereof, and a rotary cylindrical member provided with 80 sets of corresponding ratio of variables and adapted to be adjusted to present a set of ratios to form a guide.
7. A calculator of the class described including a casing having a plurality of scales evaluated with reference to two variable characteristics, operating levers having pointers movable over the scales, rotary indicating drums connected with and actuated by the levers for registering the 85 amounts of the characteristics, and a rotary member having a table carrying rim associated with the drums.
8. A calculator of the class described including a casing having a plurality of scales evaluated with reference to two variable characteristics, operating levers having pointers movable over the scales, rotary indicating drums connected with and actuated by the levers for registering the 90 amounts of the characteristics, and a rotary member having a transparent table carrying rim arranged with the drums and co-operating therewith.
9. A calculator of the class described including a casing having a plurality of scales evaluated with reference to two variable characteristics, operating levers having pointers movable over the scales, rotary indicating drums connected with and actuated by the levers for registering the amounts 95 of the characteristics, and a rotary member having a transparent table carrying rim arranged over the drums and co-operating therewith. 105
10. A calculator including a casing having slots at its end portion and provided at the slots with evaluated scales, said casing being also provided at an intermediate point 110 with an opening, rotary drums located at the opening, toothed wheels connected with the drums and arranged adjacent the slots, and operating levers extending through the slots and having interiorly arranged means 115
11. A calculator including a casing having slots at its end portion and provided at the slots with evaluated scales, said casing being also provided at an intermediate point 120 with an opening, rotary drums located at the opening, toothed wheels connected with the drums and arranged adjacent the slots, and operating levers extending through the slots and having interiorly arranged means 125
12. A calculator including a casing having slots at its end portion and provided at the slots with evaluated scales, said casing being also provided at an intermediate point 130 with an opening, rotary drums located at the opening, toothed wheels connected with the drums and arranged adjacent the slots, and operating levers extending through the slots and having interiorly arranged means

for engaging and actuating the said wheels and provided with exterior pointers movable over the scales.

11. A calculator including a casing having 5 slots at its end portion and provided at the slots with evaluated scales, said casing being also provided at an intermediate point with an opening, a shaft or axle mounted in the casing, sleeves arranged in the shaft or axle, 10 drums located at the opening and carried by the sleeves, toothed wheels mounted in the sleeves adjacent the slots, and operating levers extending through the slots and having means for engaging and rotating the 15 wheels and provided with pointers moving over the slots.

12. A calculator including a casing having slots at its end portion and provided at the slots with evaluated scales, said casing 20 being also provided at an intermediate point with an opening, a shaft or axle mounted in the casing, sleeves arranged in the shaft or axle, drums located at the opening and carried by the sleeves, toothed wheels mounted 25 in the sleeves adjacent the slots, operating levers extending through the slots and having means for engaging and rotating the wheels and provided with pointers moving over the slots, and a central wheel mounted 30 on the shaft or axle between the drums and having a table carrying rim arranged over and coöperating with the drums.

13. A calculator including a casing having slots at its end portion and provided at 35 the slots with evaluated scales, said casing being also provided at an intermediate point with an opening, a shaft or axle mounted in the casing, sleeves arranged in the shaft or axle, drums located at the opening and carried by the sleeves, toothed wheels mounted 40 in the sleeves adjacent the slots, operating levers extending through the slots and having means for engaging and rotating the wheels and provided with pointers moving 45 over the slots, a central wheel mounted on the shaft or axle between the drums and having a table carrying rim arranged over and coöperating with the drum, and coiled springs located at opposite sides of the central 50 wheel and yieldably holding the same.

14. A calculator including a casing having slots at its end portion and provided at the slots with evaluated scales, said casing being also provided at an intermediate point 55 with an opening, a shaft or axle mounted in the casing, sleeves arranged in the shaft or axle, drums located at the opening and carried by the sleeves, toothed wheels mounted

on the sleeves adjacent the slots, and operating levers extending through the slots 60 and having openings receiving the sleeves and provided with interiorly arranged teeth for engaging the wheels and having pointers movable over the scales.

15. A calculator including a casing having 65 slots at its end portion and provided at the slots with evaluated scales, said casing being also provided at an intermediate point with an opening, a shaft or axle mounted in the casing, sleeves arranged in the shaft or 70 axle, drums located at the opening and carried by the sleeves, toothed wheels mounted on the sleeves adjacent the slots, operating levers extending through the slots and having openings receiving the sleeves and provided with interiorly arranged teeth for 75 engaging the wheels and having pointers movable over the scales, and springs mounted in the openings of the levers for normally holding the same out of engagement with the 80 wheels and in engagement with the casing.

16. A calculator including a casing having slots at its end portion and provided at the slots with evaluated scales, said casing being also provided at an intermediate point 85 with an opening, a shaft or axle mounted in the casing, sleeves arranged in the shaft or axle, drums located at the opening and carried by the sleeves, toothed wheels mounted on the sleeves adjacent the slots, operating 90 levers extending through the slots and having openings receiving the sleeves and provided with interiorly arranged teeth for engaging the wheels and having pointers movable over the scales, and springs mounted in the openings of the levers for normally 95 holding the same out of engagement with the wheels and in engagement with the casing, the latter having serrations or notches at the slots to engage with the levers. 100

17. A calculator of the class described, including a plurality of scales evaluated with reference to two variable characteristics, pointers coöperating with the scales and graduating means associated with the scales 105 for indicating the amounts and proportions of the variable characteristics.

18. A calculator of the class described, including a plurality of scales evaluated with reference to two variable characteristics, and graduated indicating means associated with the scales for indicating the amounts and proportions of the variable characteristics. 110

In testimony whereof I affix my signature.

ORVILLE MERTON KILE.
